UNITED STATES PATENT OFFICE.

WILLIAM BEHRENS, OF ST. LOUIS, MISSOURI.

CAR-PEDESTAL.

SPECIFICATION forming part of Letters Patent No. 416,773, dated December 10, 1889.

Application filed February 5, 1889. Serial No. 298,788. (No model.)

To all whom it may concern:

Be it known that I, WILLIAM BEHRENS, of the city of St. Louis, in the State of Missouri, have invented a certain new and useful Improvement in Car-Pedestals, of which the following is a full, clear, and exact description, reference being had to the accompanying drawings, forming part of this specification.

This pedestal is intended specially for street cars. The pedestals have capacity for lateral movement relatively to the car upon anti-friction rollers and return to their normal position by the influence of gravity.

Figure I is an outside elevation of a pedestal, showing a wheel in outline. Fig. II is a vertical transverse section at II II, Fig. V. Fig. III is a vertical transverse section at III III, Fig. V. Fig. IV is a vertical transverse section at IV IV, Fig. V. Fig. V is a vertical longitudinal section at V V, Fig. IV. Fig. VI is an under view of the sill-plate. Fig. VII is a top view of the pedestal. Fig. VIII is an inside elevation of the pedestal and body-sill. Fig. IX is an enlarged detail section at IX IX, Fig. V, showing the pedestal in its normal position, while Fig. X is a section on the same plane, showing the pedestal in its outer position.

1 is the wheel; 2, the axle; 3, the brass which bears on the axle-journal. 4 is the grease-box. No novelty is herein claimed in these parts.

5 is the sill-plate, secured to the sill by bolts 6. The plate has at each end two saddles 7, which are adapted to bear on anti-friction rollers 8. The saddles are so formed that the side 9 toward the center of the car-body fits against the roller when the pedestal is in its normal position, as seen in Fig. IV, while the other side 10 of each saddle is inclined, so that it runs upon the roller when the pedestal moves outward.

The pedestal 11 has inverted saddles 12, whose outer side 13 fits against the roller when the pedestal is in its normal position, while the other side 14 is inclined like the side 10, so that the roller will roll up the side 14 when the pedestal moves outward. It will be seen that the outward movement of the pedestal 50 will thus cause the car-body to rise, and as soon as the side strain is removed from the

pedestal the pedestal will be forced back by the weight of the car into normal position, as seen in Figs. IV and IX.

15 is a flange of the sill-plate, whose office 55 is to exclude dirt from the roller-bearings.

In order to hold the sill-plate to its bearings on the rollers 8 and to limit the side movement of the pedestal, and also to assist in bringing it to its normal position, a bolt 16 60 passes vertically through the saddles between the two rollers. The socket 17 for the passage of the bolt is elongated transversely toward the bottom, so as to allow the outward movement of the pedestal. The bolt has a 65 T-head 18, upon which it swings as the pedestal moves outward and inward. The bolt 16 passes through a rubber or other spring 19 beneath the saddle, and carries beneath the spring a cup-shaped washer 20, bearing 70 against the bottom of the spring and retained by a nut 21.

22 are studs on the pedestal, which occupy elongated cavities 23 in the sill-plate, and which may act to limit the side movement of 75 the pedestals.

24 are the rods passing axially through the springs 25, and whose upper ends occupy the elongated holes 26 of the sill-plate and sill.

Fig. IX shows the pedestal in its normal position, while Fig. X shows it moved outward. The rollers 8 have collars 27 at the ends, which are adapted to bear against the ends of the saddles 7 and 12 and prevent the endwise displacement of either the rollers or the pedestal, 85 and which, by contact with each other, keep the rollers at the proper distance asunder, so that if the pedestal should be tilted when out of the normal position, so as to remove the weight from one of the rollers, this roller would 90 not approach the other one and thus throw the rollers out of the proper relative position.

I claim as my invention—

1. A car-pedestal carrying rollers 8, resting in saddles of the pedestal and of the sill-plate 95 5, the saddles having inclines 10 14, substantially as and for the purpose set forth.

2. The rollers 8, occupying saddles in the pedestal and sill-plate and having collars 27, substantially as and for the purpose set forth. 100

3. The combination, in a car-pedestal, of the bearing-rollers 8, working in saddles 7 12 of

the pedestal and sill-plate, and the rocking bolt 16, with spring 19 and retaining-nut 21, substantially as and for the purpose set forth.

4. A car-pedestal, rollers upon the pedestal 5 with their axes longitudinal, and a plate secured to the body-sill of the car adapted to ride on the rollers and allowing transverse movement of the body on the pedestal, substantially as and for the purposes set forth.

10 5. The combination, in a car-pedestal bearing, of a sill-plate 5 with saddles 7, adapted to

rest on the rollers 8, a pedestal having saddles 12, adapted to receive the rollers 8, collars 27 at the ends of the rollers, adapted to bear against each other and against the ends of the 15 saddles, and T-headed swinging bolts 16, connecting the sill-plate and pedestal, substantially as and for the purpose set forth.

WILLIAM BEHRENS.
